CLAIM

I claim the ornamental design a case for a mobile phone, as shown and described.

DESCRIPTION

FIG. 1 is a front perspective view of the first embodiment of a case for a mobile phone according the claimed design showing the bottom flap in a closed position;

FIG. 2 is a top view of the first embodiment of a case for a mobile phone according to the claimed design;

FIG. 3 is a bottom view of the first embodiment of a case for a mobile phone according to the claimed design showing the bottom flap in a closed position;

FIG. 4 is a front view of the first embodiment of a case for a mobile phone according to the claimed design;

FIG. 5 is a back view of the first embodiment of a case for a mobile phone according to the claimed design;

FIG. 6 is a left view of the first embodiment of a case for a mobile phone according to the claimed design;

FIG. 7 is a right view of the first embodiment of a case for a mobile phone according to the claimed design;

FIG. 8 is a front perspective view of the first embodiment of a case for a mobile phone according to the claimed design showing the bottom flap in an open position;

FIG. 9 is a front view of the first embodiment of a case for a mobile phone according to the claimed design showing the bottom flap in an open position;

FIG. 10 is a front perspective view of the second embodiment of a case for a mobile phone according to the claimed design showing the side flap in a closed position;

FIG. 11 is a top view of the second embodiment of a case for a mobile phone according to the claimed design;

FIG. 12 is a bottom view of the second embodiment of a case for a mobile phone according to the claimed design;

FIG. 13 is a front view of the second embodiment of a case for a mobile phone according to the claimed design;

FIG. 14 is a back view of the second embodiment of a case for a mobile phone according to the claimed design;

FIG. 15 is a left view of the second embodiment of a case for a mobile phone according to the claimed design;

FIG. 16 is a right view of the second embodiment of a case for a mobile phone according to the claimed design showing the side flap in a closed position;

FIG. 17 is a front perspective view of the second embodiment of a case for a mobile phone according to the claimed design showing the side flap in an open position; and,

FIG. 18 is a front view of a case for a mobile phone according to the claimed design showing the side flap in an open position.

The unshaded surfaces that are visible through the rectangular front opening, the rectangular rear opening, the opening under the bottom flap, the opening under the side flap, and the broken lines on these unshaded surfaces depict an unclaimed mobile phone. All other broken lines depict unclaimed features of the case. The broken lines form no part of the claimed design.
